GEOCHEMICAL PROSPECTING

Leo Horvitz, Houston, Tex., assignor to Esme E.
Rosaire, Houston, Tex.

Application March 10, 1941, Serial No. 382,606

20 Claims. (Cl. 23—230)

The present invention relates to a process of geochemical prospecting.

More specifically, the present invention relates to geochemical prospecting for carbonaceous deposits, such as oil, gas, coal and the like, and for structures in which such deposits may occur by the quantitative detection of leakage from the deposits themselves and from the rocks in which they are contained. Such leakage results in a deposition in the soil of evidence of the leakage and such evidence may be detected and measured by analysis of the soil. This invention relates to the broad subject matter of copending application Serial No. 107,497, filed October 24, 1936, and entitled Geophysical prospecting method.

The search for oil fields by geochemistry has heretofore been conducted by seeking actual evidence of leakage from the deposits themselves. It has been found, however, that inorganic substances not heretofore regarded as being related to the deposits themselves are indicative of proximity to buried structures which may contain the sought deposits. Thus, analyses of soil samples taken near the surface of the earth have resulted in finding variable concentrations of chlorides, the variations corresponding generally with a known structure. Many other inorganic substances are similarly indicative. Actual investigation has revealed that carbonates, bicarbonates, sulfates, sulfides, halides, basicity, acidity, total acid soluble and total water soluble constituents, etc., are suitable indicators. Practically any inorganic soil constituent may be selected as the significant constituent. The soil may be examined quantitatively for cations or anions. In certain locations examination of the soil for iron yields significant data. In other locations, some other ion may prove significant and this will ordinarily be relied upon for purposes of interpretation. Usually the content of a number of inorganic constituents in soil samples from a given area is determined and ordinarily correlation between the majority of the constituents determined will be found.

An object of the present invention is to provide a method of geochemical prospecting for buried structure capable of containing valuable deposits by the examination of surface and near surface soils for evidence therein of anomalous mineralization and secondary salt deposition.

Another object is to provide a rapid, low cost reconnaissance method of geochemical prospect-

ing which may economically be employed to evaluate large areas relative to future exploration programs.

Usually, the halo phenomenon originally observed in connection with analyses for the content of the lighter hydrocarbons and described in a paper by T. E. Rosaire, entitled, "Shallow stratigraphic prospecting over Gulf Coast structure," Geophysics III 2, March 1938, is also observable in the technique of the present invention.

It has been observed with respect to halides, which will usually be chlorides, that the pattern obtained sometimes shows high concentrations in the samples above the producing area rather than in the samples forming a fringe or halo around the producing area. Thus, when a halide profile is obtained having a single hump rather than the double hump, which usually characterizes a profile which is taken across an area which yields the halo pattern, it will be found that the hump on the halide profile will fit in the low space between the double hump on the profile shown by hydrocarbons and other constituents. On infrequent occasions this departure from the conventional pattern is also found in sulfates, which as a rule give the conventional pattern. This deviation in pattern emphasizes the desirability in practice of analyzing the soil samples over a given area for a plurality of constituents so that the anomalies appearing in the patterns resulting from the individual constituents can be compared and interrelated to produce a complete picture of the area.

In some areas it has been found that certain constituents do not yield distinctive patterns. Usually this failure to give a pattern over a producing area will be confined to one inorganic constituent and the characteristic pattern will be shown by any number of other constituents which may be determined. Thus, in prospecting according to the present method it would be unwise to condemn an area because one inorganic constituent failed to give a characteristic pattern, but the patterns of other constituents should be obtained so that it can be determined whether or not a significant pattern is obtained with the majority of the constituents. Even if a significant pattern is obtained with only one constituent, which would indeed be a rare case, further exploration of the area by the hydrocarbon technique would be in order.

Generally, it has been found that the consistency of results is better in samples of soil taken at a depth of several feet since topsoil samples are affected by leaching by meteoric waters, local fertilization, and the like. A compromise between the economy demanded by a reconnaissance method and the reasonable accuracy demanded by any exploration method indicates that a preferred form of the invention is practiced by the collection of samples from a depth of about ten feet, though, of course, the depth may be varied depending upon general conditions of climate, nature of soil, vegetation and agricultural utilization. It will be understood that all samples in a given area should preferably be collected at the same depth.

In actual practice the soil samples are collected at the same depth over a given area where this is possible. In some areas where there are outcroppings of rock or other natural impediments it often happens that the sampling depth selected cannot be continued throughout the whole area. For example, where samples are taken at eight feet at the start, it might develop later that in some certain spot it is only possible to penetrate six feet. In such cases it is preferred to take the majority of samples at the depth originally selected and take the remaining samples at as great a depth as they can be obtained. In any case, the depth at which each sample is taken is noted on the sample container for the information of the interpreter.

The practice is often followed of determining the variation with depth of the significant constituent in the sample holes at selected points along a profile. For example, in scattered holes in the area under investigation, samples are taken at one or two foot intervals in the sample hole so as to determine the variation of the significant constituent with depth. Then if all the deep samples over the area cannot be secured at the selected depth, say 12 feet, the depth determinations will aid the operator in deciding at what depth less than 12 feet he can safely take samples where they cannot be obtained at 12 feet.

Where there is already a producing well in an area under investigation it is advantageous to make depth determinations in each sample hole along a profile passing through the well. In this way the best depth at which to collect samples in the other profiles over the area in order to outline the field can be determined.

Where there is not excessive dipping of the formations it lends to uniformity to collect the samples out of the same formation so that the samples will have, as nearly as possible, the same general nature. Ordinarily strata near the surface have such a small dip that collection of the samples at a uniform depth will result in collection of the samples in the same strata. Should it transpire that, where the samples are being analyzed for a constituent, such as calcium, and during the collection of the samples a deposit high in calcium, such as limestone, is encountered, the operator will naturally take this into account and the large increase in the calcium content in samples taken in this deposit will be taken into consideration in the interpretation of the results.

The actual analysis of the collected soil samples may follow any acceptable quantitative procedure, the following table serving as examples. It should be remarked, however, that the table is exemplary only and should not be construed to define the scope of the invention.

Analyses

1. Halides:
  - a. Leach (or extract) with (distilled) water; (refluxing known weight of soil with any volume of H_2O).
  - b. Measure the H_2O extract.
  - c. Titrate with standard $AgNO_3$ solution using potassium chromate (K_2CrO_4) as an indicator.
10. 2. Bicarbonates:
  - a. Heat and dry sample.
  - b. Heat at higher temperature below decomposition temperature of carbonates, say $300^\circ C$. to decompose bicarbonates.
  - c. Measure CO_2 evolved; or titrate with standard HCl to phenolphthalein endpoint, and then titrate to methyl orange endpoint. Where samples show negligible quantities of soluble carbonates, titration to phenolphthalein endpoint may be omitted.
25. 3. Soluble sulfates:
  - a. Extract with distilled water.
  - b. Add excess $BaCl_2$ to extract to ppt. SO_4 and titrate unused $BaCl_2$ with Na_2CO_3 , using phenolphthalein as indicator; or
  - c. Titrate water extract with $BaCl_2$ using tetra-hydro-quinone as indicator.
30. 4. Sulfites:
  - a. Titration of water extract with standard potassium iodate and KI mixture, starch indicator.
35. 5. Acidity (and basicity):
  - a. By titration or pH measurements.
36. 6. Water soluble constituents:
  - a. Extract with distilled H_2O ; evaporate extract to dryness. Weight residue.
40. 7. Acid soluble constituents:
  - a. Extract with acid; evaporate extract and weigh residue.
45. 8. Carbonates (and bicarbonates):
  - a. Decompose with acid and measure CO_2 evolved by volume or weight.
50. 9. Sulfides:
  - a. Decompose with acid and measure the evolved H_2S as by precipitating the sulfide of a selected metal from a solution of one of its salts and weighing the precipitate.
55. 55. The constituent selected for determination will usually occur as a minor constituent of the soil sample, and may be present only in minute amounts. In some areas, however, the constituent selected as the significant constituent may constitute a very substantial portion of the soil sample. For example, in one area in which the samples were collected from caliche deposits and the variations in acid-soluble constituents, largely
60. 60. carbonates, were determined, an anomaly was obtained on the basis of the acid-soluble content which corresponded substantially with the anomaly prepared by analyses of samples for hydrocarbons. In many of these samples the acid-soluble components constituted more than 50% by weight of the sample. It is preferable to examine the samples for those constituents which are readily soluble in water or common inorganic acids.
65. 65. A feature of considerable importance of the present invention is the discovery of the fact that in soil samples containing carbonates, it appears that the carbonates envelope not only organic matter but also inorganic compounds. For example, when it is desired to analyze soil samples for chlorides, ordinary extraction of the sample

followed by titration, as indicated above, may reveal only negligible amounts of chlorides. If the sample is first treated with nitric acid or sulphuric acid, however, and then extracted and titrated, large amounts of chlorides may be found. Likewise, when it is desired to analyze for nitrates, it is extremely advantageous to first treat the sample before extraction with sulphuric or hydrochloric acid. It will be understood that the extraction itself can be effected with a dilute acid of the type desired. This same acid treatment is advantageous for analyses for all inorganic constituents.

The usefulness of this method has been demonstrated in practice in that when exploration has been conducted in areas also explored by other methods, the method was found to give information similar to that obtained by other methods. It is not intended to imply that it gives substantially the same information in all cases as geochemical exploration by analysis of soil samples for, say, ethane. The patterns resulting from the method of the present invention thus far bear a similarity to those resulting from the hydrocarbon technique.

In order to demonstrate the resemblance between the patterns obtained by the procedure of the present invention and those obtained by the analysis of samples for hydrocarbons, profiles of areas obtained by actual exploration by these methods are shown in the accompanying drawings in which—

Fig. 1 is a plan showing the sample locations along two lines, A—A' and B—B', in an area explored and the portion of the halo brought out by these two lines;

Fig. 2 is a series of profiles obtained by analyses of the samples taken along the line A—A' by determination of various constituents;

Fig. 3 is a similar set of profiles obtained by corresponding analyses of the samples taken along the line B—B';

Fig. 4 shows two profiles obtained by analyzing samples collected along parallel lines in a given area for ethane and higher hydrocarbons;

Fig. 5 is a pair of profiles obtained by analyzing the same samples for carbonates;

Fig. 6 is a map of an area which was prospected to determine the limits of production in a known field by collecting samples and analyzing them for their content of bicarbonates.

Referring to Figs. 1-3, there is shown in Fig. 1 a plurality of sample locations along two lines, A—A' and B—B', the former being numbered 1-16 inclusive, and the latter 17-32 inclusive. These samples were taken in virgin territory in which there had been no drilling and in which there was no known anomaly so far as the operators of the present method were aware. These samples were taken about 1,000 feet apart and all samples were taken at a depth of twelve feet. The samples were collected by field men who drilled holes twelve feet deep, scooped about a pint of soil from the bottom of the hole, placed each sample in a pint fruit jar having a sealed top, and forwarded them to the laboratory for analysis.

At the laboratory the various analyses on each sample were performed on separate portions thereof. For example, a portion having a weight of about 50 grams was subjected to a series of analytical steps to determine the inorganic constituents. This portion was first dried and about 10 grams of it was treated with hydrochloric acid and the volume of carbon dioxide given off was

measured to determine the carbonate content of the sample. Another 25 grams or so was digested with water and allowed to stand for 12 to 24 hours and the extract so obtained was titrated, separate portions being used, for halides and sulphates. The portion which had been treated with acid for the carbonate determination was then washed with water by a series of mixings and decantations until the finely divided material, representing clay, was removed and the remainder was dried and weighed to give a measure of the sand content of the soil.

A separate portion of the original sample was then subjected to analysis for hydrocarbons including ethane and heavier by the method described in copending application Serial No. 183,960, filed January 8, 1938. The hydrocarbons so determined were expressed in parts per billion by weight of the sample.

The profiles shown in Fig. 2 were made by plotting content of the significant constituent against sample locations. Profile No. 1 is the hydrocarbon profile designated on the drawings as "Heavy hydrocarbons" to mean ethane, propane, butane, etc., profile No. 2 is the carbonate profile, profile No. 3 is the sulphate profile, and profile No. 4 is the halide profile. It will be noted that in profile No. 1 the first hump starts between sample 3 and 4 and ends between samples 6 and 7, while the second hump starts between samples 11 and 12 and ends between samples 15 and 16. In making this profile, samples containing more than 10 parts per billion by weight of hydrocarbons were considered high, while samples containing less than 10 parts per billion by weight were considered low. It may be mentioned here that the value 10 was selected because the values of the background samples, that is, of the low samples, were all 10 or lower.

The profile of the carbonates corresponded closely to that of hydrocarbons. Here, the ordinates are expressed as percentage by weight of the sample. The significant quantity may be considered as anything in excess of 5%, and in this case the hump on the left is slightly wider than the corresponding hydrocarbon hump, while the hump on the right is slightly narrower than the corresponding hydrocarbon hump.

In profile 3 the ordinates are parts per million by weight of the sample. Here the general pattern of the other profiles is followed but it is compacted toward the center. It will be noted that samples 7 and 11 are high, and it is between these samples that production is indicated by the hydrocarbon and carbonate profiles. The area of production indicated by the hydrocarbons and carbonates, however, is larger than that indicated by the sulphates.

Again, in the case of the halides, a departure from the conventional pattern is found. In this case also, the ordinates are expressed in parts of halides per million by weight of the sample. It will be observed that high concentrations of halides seem to fall in the zone of low hydrocarbon concentrations, with the exception of sample 10. It is noteworthy that in this profile also the space between samples 7 and 11 is anomalous. Taken by itself, the halide profile would not be conclusive, but would indicate a zone of interest and, when taken in conjunction with the hydrocarbon and carbonate profiles, serves to define that zone. Experience has demonstrated that with chloride profiles, either a high over production or a high in a halo zone around the production may be expected. This

same observation has been made with respect to other water-soluble constituents.

Referring to Fig. 3, numeral 5 designates the hydrocarbon profile along the line B-B'. Here the ordinates are in parts per billion by weight of the sample. Taking 10 parts per billion as the dividing line, it will be seen that the hump on the left side of the profile begins between samples 18 and 19 and ends between samples 21 and 22, while the hump on the right side begins between samples 27 and 28 and ends between samples 30 and 31. It is to be observed that sample 8 is common to lines A-A' and B-B'. Numeral 6 designates the carbonate profile along B-B', in which the ordinates represent per cent by weight of the sample. As was the case with respect to profile A-A', the carbonate profile bears a close resemblance to the hydrocarbon profile. It is shifted slightly to the left, as a whole.

Numeral 7 designates the sulphate profile along B-B', which follows the same general pattern as the carbonate and hydrocarbon profiles. The ordinates in this case represent parts per million by weight. It will be observed that the halo is slightly displaced to the right with respect to the hydrocarbon profile.

Numeral 8 designates the halide profile along B-B', in which the ordinates represent parts per million by weight of the sample. This profile bears the same relation to the hydrocarbon profile as exists between profile 4 and profile 1. It indicates an area of interest between samples 22 and 27.

In these profiles the distances between points along the abscissa correspond to the distances between sampling points in Fig. 1. On the basis of the values obtained from the various samples, contour lines are drawn on Fig. 1 connecting similar values in much the same way as equipotential lines are drawn on potential maps of the earth's surface, and isograms are drawn on gravity meter maps. By connecting the point at which the first hump in profile 1 began with the point at which the first hump in profile 5 began, line 9 was drawn. Similarly, line 10 connects the point at which the first hump ends in profile 1 with the corresponding point in profile 5. Again, line 11 connects the point at which the second hump began in profile 1 with the corresponding point in profile 5, and line 12 connects the point at which the second hump ended in profile 1 with the corresponding point on profile 5.

It will be seen that lines 9 and 10 appear to be boundary lines of one part of a halo, and lines 11 and 12 appear to be boundary lines of another part of a halo. Accordingly, the producing area should be between lines 10 and 11. In cases where the distance between lines 9 and 10 or between 11 and 12 is great, it often happens there are two or more producing horizons, so that production might actually be found between lines 9 and 10, for example, at a depth greater than production between lines 10 and 11.

A discovery well was located between lines 10 and 11 and is designated by numeral 13. This well was a producer of oil. Its position is also indicated on the profiles by numeral 13. A second well, the position of which is designated by numeral 14 in Fig. 1, turned out to be a distillate well. These wells were drilled on the basis of the data afforded by the methods described herein.

In Fig. 4 are shown profiles obtained by analyzing samples taken, 1000 feet apart, along two parallel lines one quarter of a mile apart running

north and south over a given area. Sample locations are indicated by the numbered points along the abscissa. The ordinates represents parts per billion by weight of the samples of hydrocarbons, including ethane, propane, butane, etc. (referred to collectively on the drawings as "Heavy hydrocarbons"). These samples were all taken at a depth of 12 feet, in the manner previously described.

In the profile designated by numeral 47 the value selected as the dividing line between significant and nonsignificant quantities of hydrocarbons was 50 quarts per billion. On this basis, it will be seen that, from a point between samples 17 and 18 to a point between samples 20 and 21, there is a hump, followed by a depression, and then a second hump beginning at point 26 and extending to a point somewhat beyond sample 30. From this it would be expected that in the area between sample 20 and sample 26 there would be production. It may be noted that the profile shows an initial hump X which may indicate a second producing horizon because this hump X has a counterpart in profile 49 to be described hereafter.

Referring to profile 48, it will be noted that, taking 50 parts per billion as the dividing line, there is a hump which starts some place south of sample 15 and extends to a point between samples 36 and 37, corresponding almost precisely to the terminal point of the hump between samples 20 and 21. Likewise, the second hump in profile 48 begins close to sample 42, corresponding to sample 26 in profile 47, and extends to a point north of sample 46. The upward trend at either end of this profile, strongly suggests a second producing horizon. In any event, there is a definite indication of a producing zone between sample 36 and sample 43. A distillate well 51 was situated between samples 21 and 22, corresponding to samples 37 and 38.

Referring to Fig. 5, the first profile 49 was obtained by analyzing samples 15 to 30 for carbonates in the manner heretofore described. In this profile, the ordinates represent percentage by weight of carbonates in each sample. Taking 5% as the dividing line between anomalous and ordinary concentrations, it is found that there is a hump beginning between samples 17 and 18 and ending between samples 20 and 21. There is also an initial hump Y, corresponding to hump X in profile 47. A third hump begins between samples 24 and 25 and returns to normal value at sample 26, from which point it increases progressively. It may be noted at this point that, while the corresponding hump in profile 47 was said to begin at sample 26, the hydrocarbon concentration actually crossed the 50-part-per-billion line between samples 24 and 25, and returned to the 50-part point at sample 26, from which point it increased progressively. Thus, there is a strong resemblance between the carbonate profile and the hydrocarbon profile, even to the suggestion of a second producing horizon.

Profile 50 was made by conducting the carbonate analysis on samples 31 to 46, inclusive. Here, it will be noted that the first hump begins at a point south of sample 31 and extends to a point between samples 36 and 37, while the second hump begins close to sample 41, rises sharply at sample 42, returns almost to normal at sample 43, and then rises progressively. Here, again, there is a very strong resemblance between the carbonate profile and the corresponding hydrocarbon profile 48.

Referring to Fig. 6, numeral 55 designates the edge of production as it existed in a known field prior to the application of the method of the present invention. The black dots indicate producing wells, while the black dots with a cross indicate abandoned producers. In this case soil samples were collected at the points indicated by small X's and bearing sample location Nos. 1, 2, 3, 4, 10, 11, 12, 13, 14, 20, 21, 22, 23, 24, 26, 32, 33, 34, 35, 40, 41, 42, 43, 44, 48, 49, 50, 51, 52, 57, 58, 59, 60, 61, and 62. These samples were collected at a uniform depth of 8 feet, placed in sealed jars, and forwarded to the laboratory. Here, each sample was analyzed for bicarbonates by the following procedure: digest sample with distilled water 12-24 hours, titrate aliquot portion with standardized HCl acid using methyl orange as indicator—amount of HCl required to neutralize is measure of bicarbonate present. The parts per million by weight of bicarbonate in each sample is shown by the larger number adjacent each sample location. Contents of 200 parts per million and greater were taken as significant. On this basis, contour lines were drawn, with the result that an inner line 52 was obtained representing the inner boundary of a halo, the outer boundary of which was defined by a line 53. The black circular dots between lines 55 and 52 represent the producing wells which have been drilled since the aforesaid work was done. The small circles indicate locations for new wells. The wells drilled closest to boundary line 52 have been found to yield barely their allowable and, in some cases, less than this, indicating that the edge of production was approached. Line 54 is a contour line necessitated by the high values of samples 40 and 41 as contrasted with the values of samples 42 and 48. Sufficient samples to determine the direction in which this line would go were not taken.

The profiles described above and illustrated in the drawings reveal the general nature of the results attainable by the practice of the present invention and the similarity of these results to those obtained by the prospecting method in which hydrocarbons are relied upon as the diagnostic constituents. It is to be understood that the inorganic constituents mentioned on these profiles constitute only a small part of the many inorganic constituents the variations in which have been observed. It is not to be assumed that in every case the measurement of the inorganic constituents in soil samples will yield the precise patterns shown in the drawings. It may be said that, for the most part, the patterns obtained by measurement of the inorganic constituents have the same general nature as the hydrocarbon patterns. In any case, the inorganic pattern will have an anomalous portion which can be correlated with the significant portion of the hydrocarbon pattern.

Naturally, the results of the method of the present invention leave something to the judgment of the interpreter. Should the interpreter find that a particular inorganic constituent runs low for a large number of samples and then suddenly increases to a high level, which is also maintained for a large number of samples, he will investigate to determine the nature of the formations from which the samples were procured. Likewise, when the interpreter finds a single high sample among a group of low samples, he will investigate the circumstances to determine what significance, if any, should be given to this single indication.

As in established geophysical practice, where, for example, gravitational and magnetic data are used to determine the economic feasibility of further work by seismic or other more expensive methods, the present invention offers an inexpensive technique useful in ascertaining the economic feasibility of further exploration of a given area. In this respect, it is in a position to be compared directly with the torsion balance, gravity meter, magnetometer, resistivity and electric-transient method which measure indirect evidence of the presence of structure, with the data yielding a basis for economic exploitation with more expensive methods, like the seismic which measures the structure directly, or a geochemical method which measures the direct leakage products for the sought deposits.

While the method of prospecting herein disclosed can be used as the basis for a drilling program, it appears to best advantage when used as a basis for additional prospecting before drilling. These economic factors are expressed in a paper by E. E. Rosaire entitled "Tactics and strategy of exploration for petroleum," III, Geophysics IV 3, July 1939, pp. 155-166. Thus one species of the invention comprises prospecting over a region by the disclosed method, determining the areas which may economically be exploited by a prospecting method of higher resolving power, and further exploring the thus limited areas by such methods of higher resolving power.

The methods of higher resolving power include the seismic which under favorable conditions is capable of delineating structure favorable to the accumulation of oil and gas and the soil analysis method of copending application Serial No. 103,129, which is generally applicable to the problem of determining the existence and the real extent of such accumulations. The gravimetric, magnetometric, resistivity methods and the like do not fall in the class of methods of higher resolving power as they are generally conceded to be reconnaissance methods incapable of accurate and detailed structural analysis. Therefore, the term "method of higher resolving power," as used in this specification, is limited to the seismic method and the above mentioned soil analysis method with any improvement thereon.

As this invention is a surface method and contemplates surface methods of higher resolving power, prospecting with the drill, as by core drilling, is excluded from the definition of the term "method of higher resolving power."

This application is a continuation in part of my copending application Ser. No. 304,141, filed November 13, 1939, and entitled "Method of prospecting."

In addition to the species claimed in this application there are claimed in Ser. No. 451,628, filed July 20, 1942, the determination of the hydrogen ion concentration of the soil samples, in Ser. No. 451,629, filed July 20, 1942, the determination of the total water soluble content of the soil samples, in Ser. No. 451,630, filed July 20, 1942, the determination of the total acid soluble content of the soil samples, in Ser. No. 451,634, filed July 20, 1942, the determination of the alkaline-earth metal content of the soil samples, and in Ser. No. 451,635, filed July 20, 1942, the determination of the content of bicarbonate radical in the soil samples.

The nature and objects of the present invention having been thus described, what is claimed as new and useful and is desired to be secured by Letters Patent is:

1. A method of geochemical exploration for subterranean petroliferous deposits which comprises collecting samples of soil at spaced points in the area to be investigated at a depth several feet below the surface, said depth being sufficient to eliminate the effect of surface conditions, subjecting the individual samples to an analysis for the determination of the content per unit weight thereof of a substance selected from the group consisting of ionizable inorganic salts and the component ions thereof and correlating the contents of the substance so determined in the respective samples with the locations of the samples so that the possible existence of an area of petroleum deposit may be ascertained from the orientation of samples having anomalous contents of said substance.

2. A method of geochemical exploration for subterranean petroliferous deposits which comprises collecting samples of soil at spaced points in an area to be investigated at a depth several feet below the surface, said depth being sufficient to eliminate the effect of surface conditions, subjecting each sample to an analysis for the determination of the content thereof per unit weight of each of a plurality of substances selected from the group consisting of ionizable inorganic salts and the component ions thereof and correlating the contents of the respective samples so determined with the sample locations so that the possible existence of an area of petroleum deposit may be ascertained by the orientation of samples having anomalous contents of said substances.

3. A method according to claim 1 in which the sample locations are laterally spaced from each other.

4. A method according to claim 2 in which the sample locations are laterally spaced from each other.

5. A method of geochemical exploration for subterranean petroliferous deposits which comprises collecting samples of soil at spaced points in an area to be investigated at a depth several feet below the surface, said depth being sufficient to eliminate the effect of surface conditions, subjecting the individual samples to an analysis for the determination of the content per unit weight thereof of a selected inorganic acid radical and correlating the contents so determined in the respective samples with the sample locations so that the possible existence of an area of petroleum deposit may be ascertained by the orientation of samples having anomalous contents of said acid radical.

6. A method according to claim 1 in which the sample depth is at least ten feet.

7. A method according to claim 5 in which the sample depth is at least ten feet.

8. A method according to claim 5 in which the sample locations are laterally spaced from each other.

9. The method of geochemical exploration for subterranean petroliferous deposits which comprises collecting samples of soil at spaced points in an area to be investigated at a depth several feet below the surface, said depth being sufficient to eliminate the effect of surface conditions, subjecting each sample to a treatment capable of releasing therefrom inorganic acid radicals in aqueous solution, determining the quantity of a selected acid radical in the extract from each sample per unit weight of said sample and correlating the quantities so determined for the respective samples with the sample locations so that the possible existence of an area of petro-

leum deposit may be ascertained from the orientation of the samples containing anomalous contents of said acid radical.

10. A method according to claim 9 in which, in the treatment of the soil samples referred to, each sample is extracted with a dilute acid, and the radical selected for determination is one which is not contained in said acid.

11. A method according to claim 9 in which the radical selected for determination is a halide.

12. A method according to claim 1 in which the radical selected for determination is a halide.

13. A method according to claim 1 in which the radical selected for determination is the carbonate radical.

14. A method according to claim 9 in which the sample locations are laterally spaced from each other.

15. A method according to claim 9 in which the sample depth is at least ten feet.

16. The method of geochemical exploration for subterranean petroliferous deposits which comprises collecting samples of soil at spaced points in an area to be investigated at a depth several feet below the surface, said depth being sufficient to eliminate the effect of surface conditions, subjecting each sample to a treatment capable of releasing therefrom inorganic acid radicals in aqueous solution, determining the quantity of

each of a plurality of selected acid radicals in the extract from each sample per unit weight of said sample and correlating the quantities of the selected radicals in the respective samples with the sample locations so that the possible existence of an area of petroleum deposit may be ascertained from the orientation of samples having anomalous quantities of said acid radicals.

17. The method of geochemical exploration for subterranean petroliferous deposits which com-

40 prises collecting samples of soil at spaced points in an area to be investigated at a depth several feet below the surface, said depth being sufficient to eliminate the effect of surface conditions, subjecting each sample to a treatment with an acid capable of decomposing carbonates to evolve carbon dioxide, determining the amount of carbon dioxide evolved from each sample per unit weight of each sample and correlating the quantities of carbon dioxide so determined in the respective samples with the sample locations so that the possible existence of an area of petroleum deposit may be ascertained from the orientation of samples liberating anomalous quantities of carbon dioxide.

55 18. A method according to claim 17 in which the samples are collected at laterally spaced points at a depth of at least ten feet.

19. A method of geochemical exploration for subterranean petroliferous deposits which comprises collecting samples of soil at spaced points in the area to be investigated at a depth several feet below the surface, said depth being sufficient to eliminate the effect of surface conditions, determining the chloride content per unit weight of each of the respective samples, and determining the location of petroliferous deposits by selecting the significant high chloride values and correlating the same with reference to the locations at which samples yielding such significant high values were obtained.

70 20. A method according to claim 19 in which the samples are laterally spaced from each other and are collected at a depth of about ten feet.
